Patented Apr. 17, 1973

226,729

COMBINED LANTERN AND INSECT KILLER

Robert E. Iannini, Milford, N.H., assignor to
Rid-O-Ray Inc., Milford, N.H.

Filed May 17, 1971, Ser. No. 144,396

Term of patent 14 years

Int. Cl. D26—03; D22—06
U.S. Cl. D48—24

FIG. 1 is a front elevational view of a combined lantern and insect killer, embodying my new design, the rear being a mirror image of the same;

FIG. 2 is a side elevational view, the opposite side being a mirror image of the side shown;

FIG. 3 is a top plan view; and

FIG. 4 is a bottom plan view thereof.

I claim:

The ornamental design for a combined lantern and insect killer, substantially as shown and described.
